UNITED STATES PATENT OFFICE.

FRANCIS G. BUTLER, OF WEST HARTFORD, CONNECTICUT, ASSIGNOR TO
VERMONT FARM MACHINE COMPANY.

MILK-SETTING APPARATUS.

SPECIFICATION forming part of Reissued Letters Patent No. 9,302, dated July 20, 1890.

Original No. 194,510, dated August 22, 1877; Reissue No. 8,721, dated May 27, 1879. Application for reissue filed

March 11, 1880.

To all whom it may concern:

Be it known that I, FRANCIS G. BUTLER, of West Hartford, county of Hartford, State of Connecticut, formerly of Bellows Falls, Vermont, have invented certain new and useful Improvements in Milk-Setting Apparatus; and I do hereby declare that the following is a full, clear, and exact description thereof, that will enable others skilled in the art to 50 which it appertains to make and use the same, reference being had to the accompanying drawings, and to the letters of reference marked thereon, which form a part of this specification.

15 My improvements relate to the raising of cream from milk placed in closed vessels; and they consist in a novel mode of excluding the air and all foreign and deleterious matters and gases from the milk, and also in a simple mode 20 of ascertaining when all the milk has been drawn off from the vessel, so as then to stop the flow and leave the cream alone in the vessel.

In the William Cooley method of setting and 25 raising cream his cans are placed in water at a low temperature and the covers positively held down to the can by weights or fastenings, and the cans then placed in water, which may be deep enough to entirely submerge the can.

30 I avail myself of the covered can and the cooling of the filled can by depositing the same in water; but in order to secure an equalization of temperature to the inclosed milk I do not entirely submerge the covered can, nor 35 need the water in the tank reach up to the bottom line of the can-cover; but, on the contrary, I employ a hood or outer cover of fibrous or textile or kindred material, such as felt, blanketing, &c., which is capable of readily 40 absorbing and drawing up water by capillary attraction, so as to become saturated therewith.

To describe my invention more fully I refer to the drawings, which illustrate one form of simple apparatus for practicing the same.

45 Figure 1 is a perspective view; Figs. 2 and 3, vertical sections, and Fig. 4 a detail showing a modified form of cover.

A is an outer tank, vessel, or box for holding water, and also for receiving the milk ves-

sel or can B, and it is provided with a lid by 50 which it may be closed, and preferably has an outlet or spigot to facilitate the running off of the water when desired. The milk-vessel B may be of any appropriate material—say 55 tin—and of any desired shape, but preferably cylindrical, and its cover C may be of any kind so long as it be capable of shedding water so as not to allow it to drop into the milk. Over this cover I place a fibrous or kindred textile material, D—for example, a felted, woven, or 60 knitted goods—which may be secured to the cover, and of sufficient size to permit its lower edges to drop into the water within the tank, this cover forming a sort of hood, whose edges reach downward into the water. 65

When the milk has been placed in the can and the latter placed in the tank, either before or after the cool water (preferably about 45° Fahrenheit) has been put into it, and the cover put on, and the felt or other absorbent has its lower edge in the water and the hood applied, which may be previously wetted—say by the act of pouring the water into the tank—it will be seen that by capillary attraction the hood D will be kept constantly wet, thus giving an even temperature to the entire can and perfectly excluding from the inclosed milk all foreign matter and atmospheric influences. 75

A blanket laid over the cover and dipping into the water will produce the same effect, 80 and if the tank be large enough one blanket may serve for a number of cans.

As before remarked, by this improved method the total immersion of the can and its cover under water, or the filling of the tank up to and 85 above the lower line of the cover, and the need of a weight or other device to fasten the cover down is not necessary, and less labor is used in supplying or disposing of the water.

I draw off the milk from below the raised 90 cream by means of an outlet at or near the bottom of the can, on the same general principle as in the Cooley process, leaving the cream in the can; but instead of an adjusting tube or device, previously adjusted to automatically arrest the flow when the milk has 95 all been discharged, I place in the vertical wall of the can a small pane of glass, mica, or

other translucent material, *e*, made water-tight, and near to the outlet or cock *f*. Now, when the cream is raised, (which is greatly accelerated under the closed and cooling process,) and it is desired to draw off the milk from beneath this body of cream, the outlet at *f* is opened and the milk drawn off as gradually as may be desired without agitating or disturbing the cream, and when the cream becomes visible through the pane *e* and its lower line has descended till it reaches the bottom of the can the outlet or stop-cock *f* is closed, the flow of milk is cut off, and all the cream remains. The cream alone may now be either drawn off into another vessel or may be emptied from the can.

I claim—

1. In an apparatus for raising cream from milk, the combination, with the milk-can and its cover *C*, of the hood or outer cover, *D*, made of material adapted to serve as an absorbent and retainer of water, substantially as and for the purposes set forth.
2. An improved vessel for milk-setting and cream-separation provided, as described, with a transparent pane at its bottom part, and with an outlet or cock at or near its bottom line, substantially as and for the purposes set forth.

3. The improved process of milk-setting and cream-separation, which consists in placing the fresh milk into a vessel provided with a transparent pane and outlet-cock, and thereafter, when the milk has set and the cream-layer formed, withdrawing the volume of milk from beneath the cream, the line of separation and the limit of outflow being determined in operation by the pane and the outlet-cock, respectively.

4. A milk-setting apparatus composed of the following elements, viz.: an outer water tank or vessel provided with a hinged lid or cover, a milk-receptacle placed within said tank, and means for supporting the milk-receptacle above the bottom of the tank, said milk-receptacle being also provided with a double cover, the lower one of which is of metal and the other of fibrous or textile material, a bottom outlet, and a transparent panel, the whole arranged and operating in the manner and for the purpose specified.

In testimony that I claim the foregoing I have hereunto set my hand this 8th day of March, A D. 1880.

FRANCIS G. BUTLER.
